UNITED STATES PATENT OFFICE.

WILLIAM SNEDDON, OF BURRTON, KANSAS.

ENGINE-GOVERNOR.

SPECIFICATION forming part of Letters Patent No. 247,426, dated September 20, 1881.

Application filed February 4, 1881. (No model.)

To all whom it may concern:

Be it known that I, WILLIAM SNEDDON, of Burrton, in the county of Harvey and State of Kansas, have invented a new and useful Improvement in Engine-Governors, of which the following is a specification.

My invention is applicable to all governors employing fly-balls for movement of the valve, and has for its object to secure more perfect uniformity in the speed of engines with which such governors are employed.

My invention consists in a curved lever carrying a rolling weight, combined with the valve-stem of the governor in such manner that the weight is shifted nearer to the lever-fulcrum as the speed decreases, and vice versa, thereby increasing and decreasing the resistance of the governor to the speed.

In the accompanying drawings, Figure 1 is a side elevation, partially sectional, of a governor containing my improvement, and Fig. 2 is a cross-section of the lever.

Similar letters of reference indicate corresponding parts.

25 A is the stand of the governor, in which the valve-stem *a* is fitted to slide vertically.

B B are the balls, hung by arms *b* to the revolving upper part of the stand, and connected to valve-stem *a*, as usual.

30 On the bottom plate of stand A is fixed a post, *c*, in the slotted upper end of which is pivoted a curved arm or lever, *C*, that has its shorter arm extended beneath a lug, *e*, on valve-stem *a*. The lever *C* curves upward from post *c*, and is grooved lengthwise or formed trough-shaped, as shown in Fig. 2, to receive the ball *f*. The lever is also provided with guide-rods *g* at each side, which prevent the ball from fall-

ing out. The post *c* passes through an aperture in the bottom plate of the stand, and is 40 clamped by a nut at each side of the plate, so that it may be raised and lowered as desired to vary the inclination of lever *C*.

In operation, the speed being normal and valve-stem *a* moved down by rise of balls B, 45 the lever *C* is correspondingly raised at its outer end and ball *f* rolls toward post *c*. If the speed is checked from any cause, the fall of balls B causes the rolling weight *f* to roll outward; then as speed increases the weight 50 *f* returns inward. Thus a tension, increasing and decreasing as required, is kept on the valve-stem *a* and sudden movements of the stem are prevented.

The moving weight *f* may be fitted to slide 55 instead of rolling, as shown.

I am aware that it is not new to use a weight suspended from a lever by an arm attached to a friction-roll running in the slot of a vibratory lever, or to use mercury running in a cavity of 60 the vibratory lever; but

What I claim as new is—

1. In a steam-engine governor, the combination, with the lever *C*, of a ball, *f*, arranged to run loosely in a groove thereof, as and for 65 the purpose specified.

2. In an engine-governor, the grooved lever *C*, ball *f*, running loosely in the groove, post *c*, sliding valve-stem *a*, and fly-balls B, combined for operation substantially as shown and 70 described.

WILLIAM SNEDDON.
